[57] ABSTRACT

A fabric softening composition comprising a compound of formula I

in which R¹, R² and R³ are independently selected from C₁—C₄ alkyl groups or C₂—C₄ alkenyl groups, a is from 1 to 4, x[−] is a compatible anion and R⁴ and R⁵ are independently selected from C₁₂—C₂₂ alkyl or alkenyl groups, the sum of the chain lengths of R⁴ and R⁵ preferably being at least 30.

12 Claims, No Drawings

agents, enzymes, optical brightening agents, opacifiers, anti-shrinking agents, anti-wrinkle agents, anti-spotting agents, germicides, fungicides, anti-oxidants, anti-corrosion agents, drape imparting agents, antistatic agents and ironing aids.

The invention will now be illustrated by the following non-limiting examples. In the examples all percentages are expressed by weight.

Comparative Examples are designated by letters, while Examples of the invention are designated by numbers.

Preparation of Examples

The following liquid examples were prepared by adding the fabric softening compound to water at 80° C. and stirring the mixture to form a homogeneous dispersion.

The powdered examples were prepared by grinding the fabric softening compound to form a fine powder.

Softness Evaluation

Softening performance was evaluated by adding 0.1 g of softening active (2 ml of a 5% a.d. dispersion) to 1 litre of tap water, 10° FH., at ambient temperature containing 0.001% (w/w) sodium alkyl benzene sulphonate (ABS) in a tergotometer. The ABS was added to simulate carryover of anionic detergent from the main wash. Three pieces of terry towelling (8 cm x 8 cm, 40 g total weight) were added to the tergotometer pot. The cloths were treated for 5 minutes at 65 rpm, spin dried to remove excess liquor and line dried overnight.

Softening of the fabrics was assessed by an expert panel of 4 people. Each panel member assessed two sets of test cloths. Each set of test cloths contained one cloth of each test system under evaluation. Panel members were asked to assign a softness score to each cloth. To aid them in the assessment they felt 3 standard cloths whose softness had been pre-assessed as respectively 2, 5 and 8. Lower values are indicative of better softening. Water has a softness value of 8.

EXAMPLES 1-4

Examples were prepared having the following formulations:

TABLE 1

Example No.	Active	Level wt %
1	C ₂₈ betaine ester chloride	5
2	C ₃₂ betaine ester chloride	5
3	C ₃₄ betaine ester chloride	5
4	C ₃₆ betaine ester chloride	5

The remainder of the formulation comprises water.

Softness/Value

1	4.75
2	4.75
3	4.25
4	34.5

EXAMPLES 5 to 8

Examples were prepared having the following formulation and softening properties.

TABLE 2

Example	5	6	7	8
C ₃₆ betaine ester	5	4.75	4.5	4
Genopol T250*	0	0.25	0.5	1
Water	95	95	95	95
Softness Value	3.5	2.5	4	3

10 Genopol T250 (ex) is the trade name for tallow 25EO ex Hoechst.

EXAMPLES 9 to 12

15 To demonstrate the effect of the presence of fatty acids the following examples were prepared.

TABLE 3

Example	9	10	11	12
C ₃₆ betaine ester	5	4.375	4.17	3.75
Fatty Acid*	0	0.625	0.83	1.25
Water	95	95	95	95
Softness Value	3.5	3.5	4.5	5.0

25 *fatty acid is Pristerine (Trade Mark) 4916 ex Unichema (hardened tallow fatty acid).

EXAMPLES 13 to 16

30 The following powdered formulations were prepared from 100 wt % betaine ester. Their softening properties were evaluated.

Example	Softness Value
13	C ₂₈ betaine ester
14	C ₃₂ betaine ester
15	C ₃₄ betaine ester
16	C ₃₆ betaine ester

40 We claim:

1. A fabric softening composition comprising a compound of formula 1:

45 in which R¹, R² and R³ are independently selected from C₁-C₄ alkyl groups or C₂-C₄ alkenyl groups, a is from 1 to 4, X⁻ is a compatible anion and R⁴ and R⁵ are independently selected from C₁₂-C₂₂ alkyl or alkenyl groups.

50 2. A fabric softening composition according to claim 1 in which R⁴ and R⁵ of formula 1 have chain lengths which are independently selected from C₁₂-C₂₂ alkyl or alkenyl groups and wherein the sum of the chain lengths of R⁴ and R⁵ of formula 1 is at least equal to 30.

55 3. A fabric softening composition according to claim 1 in which the alkyl or alkenyl groups R⁴ and R⁵ of formula 1 are predominantly linear.

60 4. A fabric softening composition according to claim 1 which further comprises fatty acid or fatty alcohol or mixtures thereof.

5. A fabric softening composition according to claim 4 in which the fatty acid or fatty alcohol or mixtures thereof is from about 0.1 to about 50% by weight of the compound of formula 1.

6. A fabric softening composition according to claim 1 which is in liquid form.

7. A fabric softening composition according to claim 6 which comprises from about 3 wt. % to about 50 wt. % of the compound of formula 1.

8. A fabric softening composition according to claim 6 in which R⁴ and R⁵ of formula 1 together have from about 34 to about 38 carbons.

9. A fabric softening composition according to claim 1 which is in powdered form.

10. A fabric softening composition according to claim 9 in which R⁴ and R⁵ of formula 1 together have chain lengths whose sum is less than or equal to 32.

11. A fabric softening article for use in a laundry dryer, comprising a fabric softening composition as claimed in claim 1 coated on a sheet.

12. A process for softening fabrics comprising applying a composition according to claim 1 to said fabrics.
